[57] CLAIM

The ornamental design for a tray for carrying out chemical and biological tests, substantially as shown and described.

DESCRIPTION

FIG. 1 is a perspective view of a tray for carrying out chemical and biological tests showing our new design; FIG. 2 is a front elevational view thereof;

FIG. 3 is a side view thereof;

FIG. 4 is a top view thereof;

FIG. 5 is a sectional view thereof taken on line V—V of FIG. 1; and,

FIG. 6 is a sectional view thereof taken on line VI—VI in FIG. 1.

Fig. 2.

Fig. 3.
